UNITED STATES PATENT OFFICE.

WILLIAM EMMET ANDERSON, OF WASHINGTON, DISTRICT OF COLUMBIA.

DESIGN FOR A COTTON-BALE.

SPECIFICATION forming part of Design No. 24,686, dated September 17, 1895.

Application filed January 7, 1895. Serial No. 534,142. Term of patent 14 years.

To all whom it may concern:

Be it known that I, WILLIAM EMMET ANDERSON, a citizen of the United States, residing at Washington, in the District of Columbia, have 5 invented a certain new and useful Design for a Cotton-Bale; and I do hereby declare the following to be a full, clear, and exact description of the invention, which will enable others skilled in the art to which it appertains to 10 make and use the same.

My invention relates to a new, useful, and original design for cotton-bales, said design having reference more particularly to the shape and configuration of the bale.

15 The leading or characteristic features of my design consist in a cotton-bale of a cylindrical shape or configuration, having substantially plane ends, with the edges of the bale slightly rounded and the walls thereof having 20 a series of annular grooves or constrictions.

In the accompanying drawings, Figure 1 is a perspective view of a cotton-bale embodying my design, and Fig. 2 a sectional view.

From an inspection of the drawings it will be seen that the new and useful design which I have invented and produced for cotton-bales consists in a bale of a cylindrical shape, the diameter of the bale being somewhat greater than the length thereof, the ends being substantially plane, the edges being rounded slightly, as shown, and the walls being provided with a series of annular grooves or constrictions.

What I claim as new, and desire to secure by Letters Patent, is as follows:

The design for a cotton bale herein shown and described, the same being of a cylindrical shape with flat ends, with edges slightly rounded and with annular grooves or constrictions on the walls thereof.

In testimony whereof I affix my signature in presence of two witnesses.

WILLIAM EMMET ANDERSON.
